COMBINATION UNDERGARMENT

Jacob Scherfer, Chicago, Ill.

Application September 30, 1936, Serial No. 103,400

3 Claims. (Cl. 2-41)

This invention relates to improvements in ladies garments, and particularly to a combined girdle and pants.

An object of this invention is to provide a single garment having an upper portion in the form of a girdle or abdominal supporter, and a lower portion in the form of pants or "briefs" smoothly joined together so as not to cause a bulge in the outer garments, as is the case when two separate garments are worn.

Another object relates to the method of joining the two portions of the garment so that they will cooperate with each other, the portion forming the girdle being of elastic material that will stretch in all directions, and the pants portion being of relatively inelastic material.

Another object relates to the method of holding the girdle portion of the garment from being longitudinally displaced or wrinkled and to hold it smoothly in place by means of an anchoring thigh band portion of the pants.

Other objects relate to various features of construction and arrangement which will be apparent from a consideration of the following specification and drawing, wherein:

Figure 1 is a rear elevation of the garment, and,

Figure 2 is a section thereof on the line 1-1.

Figure 3 is a rear elevation of the garment.

Figure 4 is a front elevation of the garment in its stretched and applied position.

Figure 5 is a front elevation partly broken away showing a variation in the construction of the garment, being viewed along line 5-5 of Figure 6, and,

Figure 6 is a section thereof on the line 6-6 of Figure 5.

In the drawing, 10 indicates the girdle portion of the garment which is preferably in the form of a narrow tube, and consists in the preferred form, of a heavy, loosely knit elastic material adapted to stretch longitudinally and laterally or circumferentially. The upper edge of the girdle portion may be finished off with an elastic waistband 11 adapted to yield circumferentially. The lower portion of the girdle dips downwardly from the sides to the center preferably in the curved form 12 shown, so that the girdle will encompass and compress the abdomen and a portion of the hips.

The pants portion 13 is preferably abbreviated and formed of relatively sheer material, and has leg pieces or thigh engaging portions 14, which are preferably formed of ribbed material designed to yield circumferentially to snugly engage the

thigh, as shown in Figure 4. The crotch portion 15 is in the form of an inverted V shaped gusset, and preferably is formed of a double thickness of material.

As the girdle portion is elastic and the pants portion is relatively inelastic, provision is made at their point of jointure so that they will expand together. This is done by making the linear measurement of the pants portion of a predetermined size and Shirring it as at 16 at its margin where it is stitched to the elastic portion 17, so that they will both lie smooth and flat when expanded and worn, as shown in Figure 4.

In the use of girdles of the type shown that do not have stays, it is necessary to provide a means 15 to hold the girdle stretched longitudinally, as otherwise it will curl up or buckle and not provide proper support, and also cause irregularities in the outer garments. To offset this, depending garters are usually attached to the girdle to be fastened to stockings. This causes great 20 wear and tear on the stockings, and the method is not adapted to the wearing of short length stockings. Sometimes crotch pieces are provided, but this expedient causes too great tension at some portions and not enough at others. By the 25 construction herein set forth the use of depending garters has been eliminated and a means to hold the girdle uniformly stretched is provided. Furthermore, the lines of stitching 18 extending from the thigh pieces 14 to the center of the 30 curved portion or dip 12 form a reinforcement and a divided line of tension to keep the girdle stretched over the abdomen without causing undue strain on the gusset 15. The seat of the 35 pants may be formed of one piece as 19, and secured to the front portion by the side lines of stitching 20, so as to further aid in holding the sides of the girdle stretched over the hips.

In the use of tubular elastic girdles it is often 40 difficult to remove the garment after wearing it for some time. However, in my construction the difficulty is minimized as the garment can be drawn downwardly over the hips by means of the pants portion which can be more readily 45 gripped and tension obtained around the entire circumference.

In the optional form of construction shown in Figure 5 the elastic material extends only over the front of the garment to form an abdominal supporter 21, the back portion being 50 preferably formed of the same material as the pants portion. Otherwise, the construction of the front and remainder of the garment remains the same as in the other form.

Although I have shown and described certain features of my improvements for the purpose of illustration, it will be apparent to one skilled in the art that various changes may be made in the details and form of construction without departing from the spirit of the invention, and therefore, I do not wish to be restricted thereto except as so limited by the appended claims.

What I claim is:

- 10 1. In an article of the class described, a girdle portion formed of relatively heavy elastic material and a pants portion formed of relatively light weight material in comparison therewith, the said portions being cooperatively joined to each other to form a unitary garment, the said pants portion having constricting leg bands adapted to encircle the thigh of the wearer and to hold the said girdle portion anchored in stretched constricting relation, and inverted V-shaped lines of stitching on said pants portion extending from said leg bands to the bottom edge of said girdle portion to assist in holding said girdle portion stretched downwardly over the abdomen of the wearer.
- 15 2. An undergarment of the class described comprising an endless tubular girdle portion of relatively heavy elastic material and a pants portion of relatively light weight material in comparison therewith, the said pants portion being

cooperatively joined to said girdle portion by shirring and stitching said pants portion thereto, constricting terminal leg bands on said pants portion adapted to encircle the thigh of the wearer, and inverted V-shaped lines of stitching extending from said leg bands to the bottom edge of said girdle portion adapted to cooperate with said leg bands to hold said girdle portion extended downwardly over the abdomen and hips of the wearer.

10 3. An undergarment of the class described comprising an abdominal constricting portion formed of relatively heavy elastic material and a pants portion of relatively light weight material in comparison therewith, the said relatively heavy elastic material being adapted to extend over the abdomen of the wearer, and the said relatively light weight material extending from the bottom of said undergarment to the top thereof at its back portion, the said pants portion having constricting leg bands adapted to hold said portion of relatively heavy elastic material in longitudinally stretched relation on the body of the wearer, and inverted V-shaped lines of stitching on said pants portion extending from said leg bands to the bottom edge of said abdominal constricting portion to assist in holding it downwardly extended.

JACOB SCHERFER.
